UNITED STATES PATENT OFFICE.

ROBERT F. JOHNSON, OF SEATTLE, WASHINGTON.

ROTARY DISPLAY RACK.

Application filed July 28, 1924. Serial No. 728,779.

To all whom it may concern:

Be it known that I, ROBERT F. JOHNSON, a citizen of the United States, and a resident of Seattle, county of King, State of Washington, have invented a new and useful Rotary Display Rack, of which the following is a specification.

The present invention relates to improvements in display racks and its particular object is to provide a device which allows a plurality of sheets of wall paper, linoleum samples, window shades, pictures of various kinds, and the like, to be successively displayed to the purchasing public. It is particularly proposed to provide a device of this character in which the sheets or leaves to be displayed are arranged in book form, that is as a block of leaves fastened together at one end and allowing the other end to be turned over one after the other for the purpose of displaying the next leaf. One object of the invention is to allow this turning over of the single leaves to be brought about by mechanical means not requiring the constant attention of an operator. A further object of the invention is to provide means for automatically turning over the whole book after the last leaf has been turned, whereby the whole book returns to its initial position and which allows the leaf turning operation to be continued indefinitely without requiring the aid of an attendant. Further objects and advantages of my device will appear as the specification proceeds.

The preferred form of the invention is illustrated in the accompanying drawing in which Figure 1 shows a front view of my device; Figure 2 a side view of the same; Figure 3 a sectional view taken along line 3-3 of Figure 1; Figure 4 a sectional view taken along line 4-4 of Figure 2; Figure 5 an enlarged detail view showing the arrangement of the turning element with the leaves; Figure 6 a detail sectional view taken along line 6-6 of Figure 5, and Figure 7 a detail view of the lower end of the back supporting the leaves. While I have shown only the preferred form of the invention, it should be understood that various changes or modifications may be made within the scope of the claims hereto attached without departing from the spirit of the invention.

Stationary standards 1 suitably braced by means of transverse members support in

bearings 3 the shaft 4, which latter has a cog wheel 6 rotatable thereon meshing with a pinion 7 mounted coaxially with a second pinion 8' meshing with a cog wheel 8'', which latter receives rotary motion from the shaft 8 of a motor 9. The cog wheel 6 is fixed to the frame 11, which latter also rotates on shaft 4, is preferably rectangular in form and shaped to straddle the block of leaves 12, the upper end of which is, together with the upper end of its backing 13, securely held and clamped in the drum 15 fast on the shaft 4. The backing 13 is made of rigid material, but jointed by means of hinges 13' in such a manner as to allow of its bending in the direction of the leaves, but to prevent any bending in the opposite direction.

The central portion of the backing 13 supports in spaced relation thereto the member 16 by means of the turn buckle 14, this member serving to give support to the leaves as they are folded over.

The frame 11 is provided at one end with two curved rails 17 forming a continuous path with the frame for the transverse shaft 18, which latter is for this purpose provided with a shoulder 19 adapted to ride in a groove 21 in the rail and with an adjacent groove 22 riding on the ridge 23 on the rail. When the frame 11 is revolved on its pivot the shaft 18 rides in the path formed by the rail 17 and the frame, and during a complete revolution of the frame the shaft 18 travels over the entire path so as to return to the point of commencement. The shaft 18 is provided with a series of hooks 24, the hooks being arranged around the shaft as shown in Figure 6 and several sets of these hooks being provided. The sheets of material to be handled by my device are perforated near their lower edges as shown at 26, the perforations in two successive sheets being arranged so as not to register and the material around their perforations being reinforced by means of metal clips 27. It will be noted that while the perforation of one sheet is arranged to register with one series of hooks on the shaft 18 the perforation in the next sheet registers with another series of hooks.

The device thus far described operates as follows: As the motor is started the frame 11 begins to revolve on the shaft 4. Assuming that at the beginning of the opera-

tion the frame 11 occupies the position illustrated in Figure 2, its lower end will rise while its upper end descends. It will be noted that where the curved member 17 joins the outer end of the frame 11 a niche 28 is provided in the rail arresting the motion of the shaft 18 for a short while so as to allow the shaft to gain a certain momentum before it is released from the niche. As soon as the lower end of the frame 11 has advanced sufficiently far to liberate the shaft 18 the same rolls downwardly on the rails 17 and while doing so its hooks 24 engage with the perforation in the uppermost sheet. As the advance of the frame 11 continues the shaft 18 will gradually be lifted away from the block of leaves by following the curve of the two rails and by the time the frame 11 has made a one-half revolution the shaft 18 will be at the opposite joint of the rails with the frame as indicated in dotted lines in the upper part of Figure 2. As the frame advances still further the shaft 18 will remain through a certain distance in the comparatively sharp corner formed between the rails and the frame, and after having advanced to a position from which the sheet will fall downward by its own weight, the motion of the shaft 18 is reversed by the engagement of a cog wheel 29 with a stationary rack bar 31 supported on the brackets 32. The cog wheel is rotated by the rack bar while passing the same in a reverse direction, whereby the hook 24 is made to disengage from the bottom end of the leaf so that the latter may now drop into the position shown in Figure 2. After dropping the edge of the leaf the end of the frame 11 continues its rotary motion, while the shaft 18 rides along the bottom face of the frame 11 toward the niche 28 in which it comes to a stop for a certain length of time sufficiently long to allow the shaft to gain a momentum for effecting its engagement with the next sheet of material. In case the shaft should hesitate to leave the niche at the proper time, two leaf springs 30 mounted on one of the transverse members 2 and obstructing the path of the shaft will start the same.

It will be seen that in this manner the leaves are turned over successively allowing a prospective purchaser to carefully review each one of the sheets which is fully exposed to him for a certain length of time.

It should be understood that some other arrangement might be substituted for the hooks without departing from the spirit of this invention. It might, for instance, be found feasible to use a magnet for the successive picking up and dropping of the lower edge of the leaves.

During this whole operation the main shaft 4 has been kept from turning by means of the tension band 31 bearing on the outer

circumference of a wheel 32 fixed to the shaft 4 by means of the set screw 33 passing through a projection 34 rising from the face of the wheel. The tightness of the tension band 31 may be adjusted by means of the wing nut 36 threaded upon the threaded end 37 of the band and bearing on a stationary element 38. The turning over of the single leaves does not affect the drum 15 or the shaft 4, so that even after all the leaves have been turned over the drum still remains in its original position. After the last leaf has been turned, the hooks on the shaft 18 engage with the lower end of the backing 13, which for this purpose is provided with any suitable catch 41 for the hooks, and in revolving the frame 11 carries with it the lower end of the backing, which latter bends on its various hinges until the upper rigid portion of the same is reached, whereupon a further revolving movement of the frame 11 will cause the rigid portion of the backing to revolve the drum 15 and with it the shaft 4 over the resistance of the tension band 31. The support 16 for the folded leaves partakes of this revolving motion, and the latter motion continues until the whole arrangement, leaves, backing and support 16, have fallen back by gravity into their initial position. If found necessary, the wheel 32, opposing the rotation of the drum 15, may be made slightly elliptical so as to offer less resistance after rotation has started.

I claim:

1. In a display stand, means for suspending a block of leaves from a support engaging one edge thereof only and a rotary frame pivoted near the support having means associated with the end thereof successively engaging the lower edges of the leaves for turning the same about the upper edge of the block for display purposes.
2. In a display stand of the character described, a block of leaves suspended from a stationary support, a rotary frame pivoted near the supporting point having means associated with the end thereof successively engaging the lower edges of the leaves and turning the same about the upper edge of the block and means for disengaging the frame from the leaves after the turning motion has been effected.
3. In a display stand of the character described, a leaf supported at its top edge and mechanical means for turning the leaf about its top edge comprising a frame pivoted to straddle the leaf having curved guide rails thereon and a shaft riding on the guide rails having means thereon falling in engagement with the lower edge of the leaf as the rails pass the same and causing the said edge to follow its course.
4. In a display stand of the character described, a leaf supported at its top edge and

mechanical means for turning the leaf about its top edge comprising a frame pivoted to straddle the leaf having curved guide rails thereon, a shaft riding on the guide rails having means thereon falling in engagement with the lower edge of the leaf as the rails pass the same and causing the said edge to follow its course, and means causing the said lower edge to be released when it has advanced sufficiently to drop by its own weight.

5. In a display stand of the character described, a leaf supported at its top edge and mechanical means for turning the leaf about its top edge comprising a frame pivoted to straddle the leaf having curved guide rails thereon and a shaft riding on the guide rails having hooks thereon falling into engagement with the lower edge of the leaf as the

rails pass the same and causing the said edge to follow its course.

6. In a display stand of the character described, a leaf supported at its top edge and mechanical means for turning the leaf about its top edge comprising a frame pivoted to straddle the leaf having curved guide rails thereon, a shaft riding on the guide rails having hooks thereon falling into engagement with the lower edge of the leaf as the rails pass the same and causing the said edge to follow its course, a cog wheel on the shaft and a fixed rack rod engaging said cog wheel when the lower edge of the sheet has advanced sufficiently to drop by its own weight for turning the shaft so as to release the leaf.

ROBERT F. JOHNSON.
